Primary Examiner — Janice Hallmark*Assistant Examiner* — Rodolfo Castro, Jr.(74) *Attorney, Agent, or Firm* — Edell, Shapiro & Finnian, LLC(57) **CLAIM**

The ornamental design for a video conference endpoint, as shown and described.

DESCRIPTION

FIG. 1 is a front perspective view of a video conference endpoint showing my new design;
FIG. 2 is a rear perspective view thereof;
FIG. 3 is a front view thereof;
FIG. 4 is a rear view thereof;
FIG. 5 is a first side view thereof;
FIG. 6 is a second side view thereof;
FIG. 7 is a top view thereof; and,
FIG. 8 is a bottom view thereof.
